(57) **CLAIM**

The ornamental design for a collapsible coffee dripper, as shown and described.

DESCRIPTION

FIG. 1 is a front elevational view of a collapsible coffee dripper showing my new design, in a collapsed configuration;

FIG. 2 is a rear elevational view thereof;

FIG. 3 is a left elevational view thereof;

FIG. 4 is a right elevational view thereof;

FIG. 5 is a top plan view thereof;

FIG. 6 is a bottom plan view thereof;

FIG. 7 is a front perspective view thereof;

FIG. 8 is a front perspective view thereof, in an expanded configuration; and,

FIG. 9 is a front perspective view thereof, in an expanded configuration in use condition.

The broken lines showing portions of the collapsible coffee dripper in FIG. 9 are for the purpose of illustrating environmental structure only and forms no part of the claimed design.
